C. C. TOMKINSON.

CONCRETE INSERT.

APPLICATION FILED JUNE 8, 1921.

1,422,636.

Patented July 11, 1922.

UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, TOWN OF CORNWALL, NEW YORK.

CONCRETE INSERT.

1,422,636.

Specification of Letters Patent. Patented July 11, 1922.

Application filed June 8, 1921. Serial No. 475,849.

To all whom it may concern:

Be it known that I, CHARLES C. TOMKINSON, a citizen of the United States, and a resident of Plainfield, county of Union, and 5 State of New Jersey, have invented certain new and useful Improvements in Concrete Inserts (Case C), of which the following is a specification.

This invention relates to concrete inserts 10 and has for its object the provision of a device of this character that shall be simple and rugged in construction and capable of manufacture at minimum cost.

The insert comprises a bar having a 15 threaded hole which, on one side opens into a compartment formed by a piece of sheet metal bent into shape around and secured to the bar, the compartment forming a pocket into which the end of the bolt which 20 passes through the threaded hole may project. The various features of novelty of the invention will appear from the detailed description thereof taken in connection with the accompanying drawing forming part of 25 this specification.

In the drawing—

Fig. 1 is a side elevation of a concrete 30 insert embodying the preferred form of the invention.

Fig. 2 is a rear elevation of the insert shown in Fig. 1.

Fig. 3 is a plan view showing the blank from which the housing is made.

Fig. 4 is a face or bottom plan view of 35 the insert shown in Figs. 1 and 2.

Fig. 5 is a side elevation of a modified form of concrete insert.

Like characters of reference indicate like 40 parts throughout the several views.

10 indicates the bar which forms the body of insert. The bar has a ledge 11 through which extends a threaded hole 12. This ledge is surrounded by a housing H whereby 45 there is provided a pocket or compartment into which the end of a bolt may extend after passing through the threaded hole. The housing is built up from a single piece of sheet metal plate 13 which is laid out as shown in Fig. 3. The tail or part 14 and 50 sides or wings 15 and 16 are bent up at right angles to the central portion 17 whereby a box-like member is formed,—the part 14 forming the roof or top, the part 17 the end, and the parts 15 and 16 the sides of the 55 housing.

The housing is secured to the bar in any desired manner, such as by riveting, spot welding or by means of the wings 15 and 16 which are provided with extensions 15' and 16' which are bent partly around the 60 bar as clearly shown in the drawing. Upward displacement of the housing is effectively prevented by the extensions which hug the curve of the bar. Downward displacement of the housing is prevented in any 65 desired manner, as for example, by means of fingers 18 which are stamped out of the plate and which extend over the ledge 11 as clearly indicated in the drawings. The bottom or face of the ledge 11 is exposed 70 as will now be readily understood to permit the insertion of a bolt into the threaded hole.

In order to permit the insert to be positioned in the mold into which concrete is 75 to be poured, nailing tabs 19 having slots 20 project from the side walls 15 and 16. As shown in the drawings these tabs are bent at right angles to the side walls 15, 16 and are 80 flush with the face of the ledge.

The bar 10 has a foot or anchor 25 which preferably overlies the ledge 11, this arrangement offering a good anchorage for the concrete-embedded insert and a means for engaging the reinforcement therein. 85

As shown in Fig. 5, the bar may be bent into the form of a stirrup 30 at the bottom of which is the threaded hole. The housing is slightly modified being built up of a pair of side plates 31. These plates are, however, 90 secured to the bar by means of fingers 32 and flanges or extensions 33 and laterally extending nailing tabs 34 are also provided.

From the above it will be seen that I have provided a heavy-duty concrete insert 95 which is simple in construction and which may be manufactured at minimum cost.

While I have described the invention with considerable particularity, I desire it to be distinctly understood that I intend no limitation other than may be imposed by the appended claims.

What I claim is:

1. A concrete insert comprising a bar having a ledge through which there is an opening, a housing extending over the opening, said housing comprising a pair of side walls and a roof, flanges bent over from the walls into contact with the bar whereby relative displacement between the bar and housing 105 110

in one direction is prevented, and means extending from the side walls over the ledge for preventing displacement of said parts in the opposite direction.

- 5 2. A concrete insert comprising a bar having a ledge through which there is an opening, a housing extending over the opening, said housing comprising a pair of side walls and a roof, flanges bent over from the walls into contact with the bar whereby relative displacement between the bar and housing in one direction is prevented, and fingers stamped out from the side walls to overlie the ledge.
- 10 15. 3. A concrete insert comprising a solid bar having a ledge through which there is an opening, a housing extending over the opening, said housing comprising a sheet metal plate bent into stirrup form and straddling the bar at the ledge, fingers stamped out of the sides of the stirrup and overlying the ledge, flanges bent over from the free ends of the stirrup into engagement with the opposite side of the ledge and bar, and nailing tabs projecting from the sides of the stirrup.
- 20 25. 4. A concrete insert comprising a bar hav-

ing a ledge through which there is an opening, a housing extending over the opening, said housing comprising a sheet metal plate bent into stirrup form and straddling the bar at the ledge, fingers stamped out of the 30 sides of the stirrup and overlying the ledge, flanges bent over from the free ends of the stirrup into engagement with the opposite side of the ledge and bar, and nailing tabs projecting from the sides of the stirrup. 35

5. A concrete insert comprising a bar having a ledge through which extends a threaded hole, a housing overlying the hole at one side of the ledge, means stamped out from the housing to extend over the ledge, flanges bent over from the housing into contact with the opposite side of the ledge, and nailing tabs extending from the housing adjacent the exposed face of the ledge.

In witness whereof, I have hereunto set 40 my hand this 18th day of May 1921.

CHARLES C. TOMKINSON.

Witness:

I. B. MOORE.
